UNITED STATES PATENT OFFICE.

HARRY J. ANDERSON, OF CHICAGO, ILLINOIS, ASSIGNOR TO MOTOR PLAYER CORPORATION, OF CHICAGO, ILLINOIS, A CORPORATION OF ILLINOIS.

AUTOMATIC MUSICAL INSTRUMENT.

Application filed January 22, 1923. Serial No. 614,241.

To all whom it may concern:

Be it known that I, HARRY J. ANDERSON, a citizen of the United States, residing at 8 Dix Street, Chicago, in the county of Cook 5 and State of Illinois, have invented new and useful Improvements in Automatic Musical Instruments, of which the following is a full, clear, concise, and exact description, reference being had to the accompanying 10 drawing, forming a part of this specification.

My invention relates to automatic musical instruments.

One of the objects of my invention is to 15 devise a construction whereby certain features of control may be incorporated into an automatic musical instrument and controlled from tracker apertures which are already utilized for controlling other instrumentalities; that is to say, the same tracker opening is used to control not only the instrumentality which it was specifically intended to control, but also at certain times to 20 control another instrumentality.

25 In the carrying out of this object, I provide a construction in which one of the instrumentalities is controlled conjointly by a plurality of tracker openings, so that it will not be operated when either one alone of the 30 tracker openings is uncovered, but will be operated when both of the openings are uncovered at the same time.

35 A further object of my invention is to provide an instrumentality for preventing "coasting" of the air-motor which drives the music-roll.

40 A further object of my invention is to provide an improved switch-pneumatic for controlling the electric motor which drives the air-pump.

Further objects will appear in the detailed description to follow and from the appended claims.

45 In the drawings in which an embodiment of my invention is shown—

Fig. 1 is a somewhat diagrammatic view of certain parts of an automatic musical instrument;

50 Fig. 2 is an elevational view of a shut-off box for preventing "coasting" of the motor;

Fig. 3 is a section on the line 3—3 of Fig. 2;

Fig. 4 is a longitudinal sectional view through the switch-pneumatic which controls the electric motor;

55

Fig. 5 is a section on the line 5—5 of Fig. 4;

Fig. 6 is a section on the line 6—6 of Fig. 4;

Fig. 7 is a section on the line 7—7 of Fig. 5;

Fig. 8 is a section on the line 8—8 of Fig. 5;

Fig. 9 is a section on the line 9—9 of Fig. 4; and

65

Fig. 10 is a section on the line 10—10 of Fig. 6.

Referring now to the drawings in detail, the construction shown therein, comprises a tracker 10, an air motor 11 for causing the 70 music-roll to travel over the tracker 10, an air pump 12 for creating air tension for operating the instrument, an electric motor 13 for driving the air-pump 12, a switch-pneumatic 14 for controlling the electric 75 motor 13, a rewind-pneumatic 15 for reversing the travel of the music-roll after the selection has been played, a shut-off box 16, for stopping the air-motor 11 when the music-roll has been rewound, and a power- 80 pneumatic 17 which may be used to control some expression device, such as a mandolin rail or the like.

In order to give a general idea of the relation of the parts and their operations, it 85 is here stated that the switch-pneumatic 14, when collapsed, opens the switch 18, and stops the electric motor 13; that the switch-pneumatic 14 is operated only when the music-roll has been completely rewound and 90 has uncovered the tracker; that at the same time the switch-pneumatic is collapsed to stop the electric-motor the shut-off device 16 is also operated to stop the air-motor 11, to prevent it from "coasting" under its own 95 momentum, and because of the air tension in the wind-chest; that the cut-off device 16 is controlled in its action not only by the tracker, but also by the switch-pneumatic 14, so that this cut-off device can operate to cut 100 off the air-motor only when the switch-pneumatic 14 is operated; and that the switch-pneumatic is controlled not only from the tracker, but also from the rewind-pneumatic

15, so that this switch-pneumatic 14 can operate to open the switch only when the air in the rewind-pneumatic 15 is under tension. The tracker 10 is shown as of standard construction, having a series of note perforations 19, in its intermediate portion, and ten additional openings, five at each end of the tracker, for controlling certain instrumentalities, such as the expression box, the mandolin rail, the bass and treble halves of the hammer rail, the sustaining pedal, the reroll, etc. The openings with which the description is particularly concerned are the three openings indicated at 20, 21, and 22, at the left hand end of the tracker in Fig 1. It may perhaps assist in the understanding of applicant's problem to state that this tracker shown here with the ten openings in addition to the note openings is becoming a standard, and if additional instrumentalities are to be used, other than those for which this standard tracker was designed, some scheme must be devised for controlling these additional instrumentalities which will not interfere with the use of the openings for the purposes intended and which will not necessitate the provision of additional openings. It may also assist in understanding the inventor's problem to state that the opening 23 is ordinarily used to control the bass half of the hammer rest rail; that the opening 20 is normally used to control the mandolin rail-pneumatic 17 and in applicant's construction, this opening is also utilized to assist in the control of the shut-off device 16; that the opening 24 is ordinarily used to control the sustaining pedal; that the opening 21 is used in some instruments to control a replay-pneumatic, which will cause the same selection to be played over and over again, and in applicant's construction this opening is also used to assist in the control of the switch-pneumatic which controls the electric motor; that the opening 22 is ordinarily used to control the reroll-pneumatic which reverses the connections to rewind the music-roll after the selection has been played, and in applicant's construction this opening is used to assist in the control of the switch-pneumatic 14; that the four openings 25, 26, 27 and 28, are used to control the expression box and that the opening 29 is used to control the treble half of the hammer rest rail; it may also assist in understanding to state that the switch-pneumatic 14 will be operated only when both of the openings 21 and 22 are uncovered, and that the cut-off device 16 will be operated only when all three of the openings 20, 21 and 22 are uncovered, and that these openings are uncovered only when the music-roll has been completely rewound and the end of the music-roll is leaving the tracker. This enables the openings 20, 21 and 22, to be used for their ordinary purposes, con-

trolled by the special perforations, without causing the operation of the devices which are operated only when a plurality of tracker openings are simultaneously uncovered. In other words, the special perforation will cause the operation of the device which it was intended to control, but will not cause the operation of the device which requires the uncovering of a plurality of openings to effect its operation. Thus the mandolin-rail-pneumatic can be operated as often as desired or as often as perforations are provided for it during the playing of the selection without causing the operating of the switch-pneumatic 14, and the rewind-pneumatic 15 can be operated by means of a special perforation at the end of the selection to reverse the connection for rewind, without causing the operation of the switch-pneumatic 14. It may also assist in understanding the construction to state that the reason why the shut-off device 16 is not operated by the ordinary perforation for the mandolin-rail, is that a coupler or cut-off device is provided in the connection between the shut-off device and the tracker, which is normally closed, and which is opened only when air tension exists in the switch-pneumatic 14, and that the reason that the switch-pneumatic 14 is not operated by means of special perforations in the music-roll which uncover the tracker opening 21 is that this switch-pneumatic is normally cut off from the tracker opening 21 by means of a coupler cut-off device which is opened only when air tension exists in the reroll-pneumatic 15. The normally closed coupler or cut-off referred to for the shut-off device 16 is located in the switch-pneumatic 14, between the ducts 30 and 31, which provide communication between the shut-off device and the tracker opening 20. The duct 31 is provided with a branch connection 32, which goes to the mandolin-rail-pneumatic 17. The coupler cut-off device 110 which normally cuts off the switch-pneumatic 14 from the tracker opening 21 is also located in the switch-pneumatic 14, and normally cuts the switch-pneumatic off from communication with the tracker opening 21 through the duct 33.

The rewind-pneumatic 15 is connected by the duct 34 with the tracker opening 22 and may be of any usual or suitable construction. The mandolin-rail-pneumatic 17 may also be of any usual or suitable construction.

The parts which remain to be described in detail are the shut-off device 16, and the switch-pneumatic 14 with the two couplers 125 embodied in it.

The cut-off device 16, shown in communication with the wind-chest 35 through the nipple 36 and tube 37, comprises a valve or cut-off member 38, mounted on a flexible 130

diaphragm 39 for controlling the port member 40, which leads to the air-motor 11. The diaphragm chamber 41 underneath the diaphragm 39, may be in communication 5 either with the atmosphere, or with the wind-chest 35. If in communication with the atmosphere, the valve or cut-off member 38 will close the port 40. If in communication with the exhaust, the valve member 38 will be moved away from the port 40, because of the relatively higher pressure of the air in the port member 40. A vent 41^a of any usual or suitable construction is provided for exhausting the air from 10 the diaphragm chamber 41 and tube 30 when the tracker opening 20 is closed. The means for controlling the pressure in the diaphragm chamber 41 will be described more in detail hereinafter, but it is here 15 stated that the diaphragm chamber 41 will be in communication with the exhaust until all three of the tracker openings 20, 21 and 22, are uncovered, which takes place only when the music-roll leaves the tracker. 20

25 Coming now to the description of the somewhat complicated switch-pneumatic 14 and the two couplers or pneumatic-cut-offs, shown in detail in Figs. 4, 5, 6, 7, 8 and 9, this comprises the bellows 42, having the 30 finger 43 for operating the electric switch 18, a tracker-controlled pneumatic-valve 44 which in one position connects the bellows 42 with the atmosphere, and in another position with the exhaust, a coupler or cut-off 35 device 45 for controlling the communication between the pneumatic-valve 44 and the tracker tube 33, and a coupler or cut-off device 46 for controlling the communication between the tube 30, leading to the cut-off 40 device 16, and the tube 31. As previously intimated, the coupler 45 is controlled by the rewind-pneumatic 15, and the coupler 46 is controlled by the bellows 42. The two coupler devices are similar in construction, 45 although it will be necessary to describe both somewhat in detail.

The pneumatic valve 44, comprises a two-faced valve 47, co-operating with the atmospheric port 48 and the exhaust port 49 respectively, a valve stem 50, guided in the valve stem guide members 51 and 52, a button 53 secured to the valve stem 50 and an actuating diaphragm 54, for controlling the valve 47. When the diaphragm chamber 55 above the diaphragm 54 is in communication with the exhaust thru the bleed hole 60, the atmospheric port 48 will be open, and the bellows 42 will be in communication with the atmosphere thru the passages 56 and 57, the valve chamber 58, and the atmospheric port 48. When the diaphragm chamber 55 is in communication with the atmosphere, the exhaust port 49 will be open and the bellows 42 will be in communication 60 with the exhaust thru the passages 56 and 57, the valve chamber 58, and the exhaust port 49. The chamber 59 underneath the diaphragm 54 is always in communication with the air-pump 12 through the port 59^a, nipple 59^b and tubes 59^c and 59^d. A bleed 70 60 of any suitable or usual construction is provided thru which the air in the diaphragm chamber 55 is exhausted when the passage 61 leading to the diaphragm chamber 55 is cut-off from the atmosphere. 75

The two couplers or cut-offs, 45 and 46, are similar in construction, but it will be necessary to describe both somewhat in detail. The coupler 45 comprises a flexible coupler diaphragm 62, this diaphragm controlling communication between the ports 63 and 64. The port 63 is at the entrance to the passage 61 previously referred to, while the port 64 leads to the tracker tube 33 through the passage 65. A bleed 66 is 80 provided of any usual or suitable construction, for exhausting the air in the passage 65 and tracker tube 33, when the tracker opening 21 is covered by the music-roll. The port 64 opens into an annular channel 90 67, surrounding the port 63, this annular channel as well as the port being overlain or covered by the coupler diaphragm 62.

This coupler diaphragm 62 is controlled by a diaphragm 68, carrying a pressure disc 69, the diaphragm chamber 70 of the diaphragm 68 being connected with the interior of the rewind-pneumatic 15 through the tube 71 and the nipple 72. 85

When the interior of the rewind-pneumatic 15 is connected with the exhaust, the diaphragm chamber 70 will also be connected with the exhaust, through the tube 71, and when the rewind-pneumatic 15 is connected with the atmosphere, the diaphragm chamber 70 will also be connected with the atmosphere. Following this out further, when the diaphragm chamber 70 is connected with the atmosphere, the pressure member 69 will bear against the coupler diaphragm 62, and will cut off communication 95 between the ports 63 and 64. When, however, the diaphragm chamber 70 is in communication with the exhaust, the pressure on both sides of the diaphragm 68 will 100 be balanced, and the pressure on the coupler diaphragm 62 will be relieved, permitting air to flow from the port 64 to the port 63, and thus establishing communication between the tracker and the pneumatic valve 44. Thus 105 when both of the tracker openings 21 and 22 are uncovered, the diaphragm-chamber 55 will be in communication with the atmosphere, and the valve 47 will be moved to close the atmospheric port 48, and open the 110 exhaust port 49, causing the collapse of the pneumatic bellows 42. 115

If, however, either one alone of the tracker openings 21 or 22 is uncovered, no action 120 of the switch-pneumatic-bellows 42 will take 125 130

place. It requires the uncovering of both of these tracker openings simultaneously to effect the collapse of this pneumatic. If the tracker opening 21 alone is uncovered, no air can get to the valve-controlling diaphragm 54, because of the coupler-diaphragm 62. If the tracker opening 22 alone is uncovered, no air will get to the valve-controlling diaphragm 54, because the tracker opening 21 will be covered by the music-roll.

With this construction it will be seen that the rewind-pneumatic 15 can be operated to rewind the music-roll without affecting the switch-pneumatic 14.

As previously intimated, the tracker opening 21 is used with some instruments to control a replay-pneumatic 72^a, connected with the duct 33 thru the valve-controlled duct 72^b. For the purpose of actuating this replay-pneumatic 72^a, the front or leader end of the music-roll is provided with a perforation, which will operate this replay-pneumatic to cause the music-roll to be drawn forward, after rewinding, to repeat the selection. If a music-roll having this replay perforation at the front end for the purpose of controlling the replay-pneumatic is used with the construction which I have described, this replay-perforation in the music-roll will have no effect on the switch-pneumatic, as the coupler 45 is normally closed, being open only when the perforation 22 also is uncovered. Thus either one of the openings 21 or 22 can be used alone for ordinary purposes without causing any effect on the switch-pneumatic 14.

Coming now to a detailed description of the other cut-off or coupler 46, which controls the air-motor shut-off device 16, this comprises a coupler-diaphragm 73, for controlling communication between the ports 74 and 75, and a controlling-diaphragm 76, controlled by the pressure in the switch-pneumatic 14 through the passage 77. The port 74 is in communication with the tube 31 leading to the tracker opening 20, (which also controls the mandolin-rail-pneumatic 17) and the port 75 is in communication with the diaphragm chamber 41 of the air-motor shut-off device through the tube 30. The controlling-diaphragm 76 either presses the coupler-diaphragm 73 to its seat to cut off communication between the ports 74 and 75, or relieves the pressure on this coupler-diaphragm to permit communication between the said ports. When the switch-pneumatic bellows 42 are in communication with the exhaust, the controlling-diaphragm 76 will exert no appreciable pressure on the coupler-diaphragm 73, while when the switch-pneumatic bellows 42 are in communication with the atmosphere, the diaphragm 76 will bear firmly against the coupler-diaphragm 73 to cut off communication be-

tween the ports 74 and 75, and thus cut off the cut-off device 16 from the control of the tracker.

A bleed 78 is provided of any usual or suitable construction for exhausting the air in the tube 31 when this tube 31 is cut off from the atmosphere.

It is obvious that the two couplers need not be incorporated in the switch-pneumatic, but might be otherwise mounted.

The operation has been outlined in connection with the description of the various constructions. To recapitulate briefly what takes place, let it be assumed that a music-roll is placed in position on the tracker, and that this music-roll is provided with a perforation near its front end which in a certain type of instrument would co-operate with the tracker opening 21 to operate a "replay" pneumatic; that it is also provided with a perforation near the rear end of the music-roll for operating the reroll-pneumatic 15 and that the intermediate portion of the music-roll may be provided with any desired arrangement of note perforations, and any desired arrangement of perforations for co-operating with the tracker openings 23, 24, 21, 22, 25, 26, 27 and 28 to control the bass half of the hammer rail, the mandolin rail, the sustaining pedal, the expression box, and the treble half of the hammer rest rail.

With such a music-roll, when the instrument is put into operation to cause the music-roll to be drawn over the tracker, the first perforation to cross the tracker will be the perforation which with certain types of instruments operates the replay-pneumatic. This will have no effect whatever on applicant's construction as shown, as the switch-pneumatic is cut off from the tracker opening 21 by the coupler 45.

As the music-roll continues, the selection will be played, and the various expression devices will be operated in accordance with the controlling perforations provided until the selection is finished, whereupon the perforation which controls the reroll-pneumatic will cross the tracker, operating the reroll-pneumatic to reverse the travel of the music-roll, (and also to cut off the action wind to prevent the selection from being played backward).

The rewinding of the music-roll will continue until the end of the music-roll leaves the tracker, uncovering all of the tracker openings. At the instant of uncovering of the tracker openings 20, 21 and 22, the reroll-pneumatic 15 will be placed in communication with the exhaust, and this will cause the diaphragm-chamber 70 to be connected with the exhaust, relieving the pressure on the coupler-diaphragm 62, and thus permitting communication between the diaphragm-chamber 55 and the tracker open-

75

ing 21. This admission of atmospheric air to the diaphragm-chamber 55, thru the uncovered tracker opening 21, causes the actuation of the valve 47, to connect the switch-pneumatic 14 with the exhaust. This causes the collapse of the switch-pneumatic and the operation of the switch to stop the electric motor 13. When the bellows 42 is thus placed in communication with the exhaust, the controlling-diaphragm 76 is also subjected to the action of the exhaust through the passage 77, and this permits the opening of the coupler-diaphragm 73 which controls the communication between the shut-off device 16 and the tracker opening 20. Thus atmospheric air is admitted to the diaphragm-chamber 41 of the shut-off device 16, through the tracker opening 20, causing the valve 38 to be pressed firmly against the port 40, to shut off the air-motor 11 from the exhaust. This instantly stops the air-motor, and prevents it "coasting".

It will be seen that I have thus provided a construction in which additional instrumentalities are provided without necessitating any additional tracker openings, and without interfering with the control of the instrumentalities already controlled by the tracker openings.

30 It is obvious that additional tracker openings might be utilized for a double purpose if desired, and this double use might extend even to include some of the note-openings in the tracker.

35 While I have shown but two such additional instrumentalities, it is obvious that other instrumentalities might be added and similarly controlled.

Having thus described my invention, 40 what I claim as new and desire to secure by United States Letters Patent is:

1. An automatic musical instrument comprising a tracker having two openings, a pneumatic device, and means whereby said pneumatic device will be operated when both of said tracker openings are uncovered, but will not be operated when either one alone of said tracker openings is uncovered.

2. An automatic musical instrument comprising a tracker having a plurality of openings, two pneumatic devices, means for affording communication between one of said tracker openings and both of said pneumatic devices, a cut-off device for one of said pneumatic devices, normally closing communication between said one of said pneumatic devices and said one of said tracker openings, and means whereby when another of said tracker openings is uncovered said cut-off device will be operated to permit communication between said one of said pneumatic devices and said one of said tracker openings.

3. An automatic musical instrument, comprising a tracker, a power pneumatic con-

trolled from said tracker, a pneumatic device provided with a duct for affording communication with one of the tracker openings, a cut-off device for said duct, normally closing communication between said pneumatic device and said one of said tracker openings, said cut-off device comprising a pressure actuated member, and means for affording communication between one side of said pressure actuated member and said power pneumatic, whereby when suction exists in said power pneumatic, said pressure actuated member will be operated for opening said duct.

4. An automatic musical instrument comprising a tracker, an air-motor for driving a music-roll over said tracker, an air-pump for creating air tension to operate said air-motor, an electric-motor for driving said air-pump, a switch for controlling said electric-motor, a switch-pneumatic for operating said switch to stop said electric-motor, and a pneumatic stop device to prevent coasting of said air-motor controlled jointly by the tracker and by the said switch-pneumatic, said switch-pneumatic having one connection with the tractor, and said stop device having another connection with the tractor controlled by the switch-pneumatic.

5. An automatic musical instrument comprising a tracker, means for driving a music-roll over said tracker, a tracker-controlled rewind-pneumatic for reversing the travel of said music-roll, an air-pump for creating air tension to operate said instrument, an electric-motor for driving said air-pump, a switch for controlling said electric-motor, and a switch-pneumatic controlled jointly by said tracker and by said rewind-pneumatic for operating said switch to stop said electric-motor.

6. An automatic musical instrument comprising a tracker having a plurality of tracker openings, a pneumatic device provided with a duct for affording communication with one of said tracker openings, a cut-off device for said duct normally closing communication between said pneumatic device and one of said tracker openings, and means whereby when another of said tracker openings is uncovered, said cut-off device will be operated to permit communication between said one of said tracker openings and said pneumatic-device.

7. An automatic musical instrument comprising a tracker, an air-motor for driving a music-roll over said tracker, a tracker-controlled rewind-pneumatic for reversing the travel of the music-roll, an air-pump for creating air tension to operate said air-motor, an electric-motor for driving said air-pump, a switch for controlling said electric-motor, a switch-pneumatic controlled jointly by the tracker and rewind-pneu-

matic for operating said switch to stop said electric-motor, and a pneumatic stop device to prevent coasting of the air-motor, controlled jointly by the tracker and said switch-pneumatic.

8. An automatic musical instrument comprising a tracker having a plurality of openings, a pneumatic device provided with a duct for affording communication with one of said tracker openings, a cut-off device for said duct normally closing communication between said pneumatic device and said one of said tracker openings, and means whereby another of said tracker openings is uncovered, said cut-off device will be operated to permit communication between said one of said tracker openings and said pneumatic device, said cut-off device comprising a member having a port therein, a diaphragm normally closing said port, an annular channel surrounding said port, and a port opening into said annular channel, said diaphragm normally closing communication between said ports but permitting communication therebetween when lifted.

9. An automatic musical instrument comprising a tracker having a plurality of tracker openings, a pneumatic device provided with a duct for affording communication with one of said tracker openings, a cut-off device for said duct normally closing communication between said pneumatic device and said one of said tracker openings, said cut-off device comprising a member having a port therein, an annular channel surrounding said port, a second port opening into said annular channel, a dia-

phragm extending across said annular channel and both of said ports, a tracker controlled power pneumatic, means affording communication between the interior of said power-pneumatic and one side of said diaphragm, whereby when suction is present in said power pneumatic, said diaphragm will be lifted to permit communication between said ports.

10. An automatic musical instrument comprising a tracker, a pneumatic device provided with a duct for affording communication with an opening of said tracker, a cut-off device for said duct normally closing communication between said pneumatic device and said tracker opening, said cut-off device comprising a port and a diaphragm normally closing said port, a power-pneumatic and means affording communication between the interior of said power-pneumatic and one side of said diaphragm whereby when suction is present in said power pneumatic, said diaphragm will be lifted to uncover said port.

11. An automatic musical instrument comprising a tracker having an opening, two pneumatic devices both connected with the same tracker opening, and a cut-off device for controlling the communication between one of said devices and said opening, the tracker having another opening which controls said cut-off device.

In witness whereof, I have hereunto subscribed my name.

HARRY J. ANDERSON.
